UNITED STATES PATENT OFFICE.

CHARLES A. STURTEVANT, OF PLAINFIELD, NEW JERSEY, ASSIGNOR TO
E. C. FULLER COMPANY, OF NEW YORK, N. Y., A CORPORATION OF
NEW YORK.

FRAME CONSTRUCTION FOR FOLDING AND OTHER MACHINES.

No. 825,429.

Specification of Letters Patent.

Patented July 10, 1906.

Application filed February 17, 1905. Serial No. 246,050.

To all whom it may concern:

Be it known that I, CHARLES A. STURTEVANT, a citizen of the United States, residing at Plainfield, in the county of Union and State of New Jersey, have invented new and useful Improvements in Frame Construction for Folding and other Machines, of which the following is a specification.

This invention relates to an improved construction of frames which are more particularly designed for machines in which attachments require support between the side pieces thereof.

The object of this invention is to produce a frame for this purpose which enables these attachments to be fitted accurately and expeditiously by means which materially reduce the cost of the same.

In the accompanying drawings, consisting of two sheets, Figure 1 is a sectional elevation of a folding-machine having its frame and the means for supporting the attachments thereon constructed in accordance with my invention. Fig. 2 is a fragmentary side elevation of one of the side and cross pieces and an attachment supported thereon. Fig. 3 is a top plan view of the main frame of a folding-machine embodying my invention. Fig. 4 is a vertical cross-section, on an enlarged scale, in line 4-4, Fig. 2. Fig. 5 is a vertical longitudinal section showing the connection between one of the side and cross pieces.

Similar letters of reference indicate corresponding parts throughout the several views.

A A represent the vertical standards or side pieces of the main frame, and B B' B² B³ B⁴ B⁵ B⁶ the horizontal cross-pieces thereof. Each of the cross-pieces consists of a pair of parallel rods or bars *b b*, which preferably are circular or cylindrical in cross-section and secured at their opposite ends to the adjacent side pieces of the frame. The ends of the rods are seated in circular or cylindrical sockets *c*, arranged on the inner sides of the side pieces. Although these sockets may be formed directly in the main frame, it is preferable to form them in separate brackets *D*, which are interposed between the ends of the rods and the side pieces. Each of these

brackets contains a pair of sockets on its inner side for receiving the adjacent ends of a pair of rods, and its back side has a flat face which bears against a corresponding flat face on the inner side of the respective side piece, 55 which faces are arranged at right angles to the rods *b*, as shown in Figs. 2 and 5. The cross-rods, brackets, and side pieces may be connected by various means, but preferably by screws or bolts *E*, which pass through 60 openings in the side pieces and brackets and bear with their heads against the outer side of the latter, while their inner screw-threaded ends engage with correspondingly-threaded openings in the ends of the rods. Each of 65 the bolts *E* is axially in line with its rod and the respective socket, and upon tightening the bolt the rod is drawn with its end against the bottom of the socket, and the bracket is drawn against the inner side of the side 70 piece. In order to cause the end of each rod to engage squarely with the bottom of its socket and insure fitting the rod and side piece together at right angles to each other, the outer end of each rod is concaved or 75 dished, as shown at *f* in Fig. 5. By this means all liability of the rod bearing only at its center against the bottom of the socket is avoided and the rod is compelled to bear all 80 around the edge or margin of its end, producing a very stiff joint between the side and cross pieces and a very rigid frame as a whole.

The rods or bars of each cross-piece may be arranged either vertically one above the other or horizontally side by side, depending upon the particular location in the frame or the character of the attachment which the same is intended to support.

Although attachments for various purposes 90 may be mounted on the cross-pieces of the frame, those shown in Fig. 1 of the drawings consist of brackets *g g*, mounted on the cross-pieces B² B⁴ and carrying the bearings in which the rollers *G* of the second folding device are journaled; a bracket *h*, mounted on the cross-piece B and supporting part of the mechanism which operates the gripper *H*, whereby the sheets are side-registered before 95 being operated upon by the blade *i* and 100

rollers I of the first folding device; brackets *j*, mounted on the cross-pieces *B²* *B³* and carrying the bearings in which the rollers *J* of the fourth book-folding device are journaled; bearings *k*, which are mounted on the cross-pieces *B²* *B⁵* and in which are journaled the upright packer or rock-shaft *K* for operating the packers of the folded signature-stacking devices, and brackets *k'* *k''*, which are mounted on cross-piece *B'* and which support the rollers *k³* and other parts of the fourth periodical-folding device. The means for fastening each of these attachments or brackets to its cross-piece consists of two clamping-plates *L* *L*, which are secured against opposite sides of the pair of rods by one or more bolts or screws *l* and either one or both of which carry parts of the particular attachment which is to be mounted on said rods. The clamping-bolts *l* preferably connect the central parts of the clamping-plates and are arranged between the rods of the cross-piece against which they bear, as shown in Figs. 1, 2, and 4.

25 The inner side of each clamping-plate is provided with a pair of concave recesses or seats *m*, which face the pair of similar recesses in the companion clamping-plate. The recesses of both plates have their axes separated the same distance as that between the axes of the rods, and the latter fit on opposite sides into the pairs of recesses in said plates, as shown in Figs. 1 and 4.

35 The several duplex rods, the sockets of the several supporting-brackets receiving the ends of the same, and the recesses of the several attachment-brackets of the machine have their axes preferably all arranged the same distance apart, as shown in the drawings. By this means the manufacture of the machine can be effected rapidly, accurately, and at reduced cost, and the parts can be made interchangeable by means of standard-jigs which are constructed suitable for fitting up all of the socket-brackets and attachment-brackets. This system of frame construction also permits of forming the recesses of the attachment-brackets so that the attachments may be supported at any desired angle relatively to the duplex rods with equal facility and also permit of easily adjusting the attachments into the required position on the rods. This is apparent from Fig. 1, in which the brackets on the cross-pieces *B* *B'* *B²* *B³* *B⁴* are either parallel or at right angles to the cross-pieces, while the bracket *k'* for supporting the fourth folding-rollers *k³* on the cross-piece *B'* is inclined or arranged at an oblique angle to the rods of this cross-piece.

40 I claim as my invention—

1. A machine-frame having a member composed of two adjacent immovable parallel bars or rods which are secured against end-

wise movement, and an attachment-supporting clamp or bracket secured to both of said bars or rods and capable of longitudinal adjustment thereon, substantially as set forth. 65

2. A machine-frame having a member composed of two adjacent parallel stationary bars or rods, and an attachment-supporting clamp or bracket having parts which bear against the opposite outer sides of the bars or rods and means for connecting said parts, substantially as set forth. 70

3. A machine-frame having a member composed of two round parallel bars or rods, and a divided attachment-supporting clamp or bracket having two parts which are provided on their opposing sides with concave recesses which receive the outer sides of said bars or rods and means for connecting said parts, substantially as set forth. 75

4. A machine-frame comprising side pieces each of which is provided on its inner side with a pair of sockets, and a cross-piece comprising a pair of parallel bars or rods having their ends seated in said sockets, substantially as set forth. 80

5. A machine-frame comprising side pieces, brackets arranged on the inner sides of the side pieces and each provided with a pair of sockets, and a cross-piece comprising a pair of parallel bars or rods having their ends seated in said sockets, substantially as set forth. 90

6. A machine-frame comprising side pieces, brackets arranged on the inner sides of the side pieces and each provided with a pair of sockets, a cross-piece comprising a pair of parallel bars or rods having their ends seated in said sockets, and bolts connecting said bars, brackets and side pieces, substantially as set forth. 95

7. A machine-frame comprising side pieces, brackets arranged on the inner sides of the side pieces and each having a pair of circular sockets the axes of which are parallel, a cross-piece comprising a pair of parallel circular rods or bars seated at their ends in said sockets, and bolts passing through said side pieces and brackets and each engaging its threaded end with one of said rods or bars, substantially as set forth. 105

8. A machine-frame comprising side pieces, brackets arranged on the inner sides of the side pieces and each having a pair of circular sockets the axes of which are parallel, a cross-piece comprising a pair of parallel rods or bars having their ends concaved and seated in said sockets, and bolts passing through said side pieces and brackets and engaging their threaded ends with the ends of said rods or bars, substantially as set forth. 110

9. A machine-frame comprising side pieces, a cross-piece connecting the side pieces and comprising a pair of parallel rods or bars, and an attachment-clamp comprising plates bear-

ing against opposite sides of the rods or bars, and a connection between said plates, substantially as set forth.

10. A machine-frame comprising side pieces, a cross-piece connecting the side pieces and comprising two parallel cylindrical rods, and an attachment-clamp comprising two plates provided in their opposing sides with pairs of concave recesses which en-

gage with opposite sides of the rods, and a bolt connecting said plates between said rods, substantially as set forth.

Witness my hand this 14th day of February, 1905.
